(57) **CLAIM**

The ornamental design for a tool cabinet, as shown and described.

DESCRIPTION

FIG. 1 is a front, top, and left perspective view of a tool cabinet showing the new design;

FIG. 2 is rear, bottom, and left perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a front, top, and left perspective view with doors in an open configuration thereof;

FIG. 10 is an enlarged detail view taken from the encircled area 10 in FIG. 1;

FIG. 11 is an enlarged detail view taken from the encircled area 11 in FIG. 1;

FIG. 12 is an enlarged detail view taken from the encircled area 12 in of FIG. 1; and,

FIG. 13 is an enlarged detail view taken from the encircled area 13 in of FIG. 2.

The broken lines shown in the figures are for the purpose of illustrating portions of the tool cabinet and form no part of the claimed design.

1 Claim, 13 Drawing Sheets
